*Primary Examiner—Melody N. Brown
Attorney, Agent, or Firm—Nixon & Vanderhye, P.C.***[57] CLAIM**

The ornamental design for a “steering wheel with air bag for motorvehicles”, as shown and described.

DESCRIPTION

FIG. 1 is a front elevational view of a steering wheel with air bag for motorvehicles showing my new design;
FIG. 2 is a left side elevational view thereof, the right side view being a mirror image of that side shown;
FIG. 3 is a top plan view thereof;
FIG. 4 is a bottom plan view thereof; and,
FIG. 5 is a rear elevational view thereof.
